(57) **CLAIM**

I claim the ornamental design for a portable collapsible toilet, as shown and described.

DESCRIPTION

FIG. 1 is a perspective view of a portable collapsible toilet, showing my new design;
 FIG. 2 is a perspective view thereof;
 FIG. 3 is a front elevational view of FIG. 1;
 FIG. 4 is a rear elevational view of FIG. 1;
 FIG. 5 is a left-side elevational view of FIG. 1;
 FIG. 6 is a right-side elevational view of FIG. 1;
 FIG. 7 is a top plan view of FIG. 1; and,
 FIG. 8 is a bottom plan view of FIG. 1.
 The broken lines in FIG. 8 illustrate environmental matter that forms no part of the claimed design.
